(57) **CLAIM**

The ornamental design for a portable medical diagnostic apparatus, as shown and described.

DESCRIPTION

FIG. 1 is a first side view of a portable medical diagnostic apparatus of the new design with a movable arm in a retracted position;

FIG. 2 is a second side view of the portable medical diagnostic apparatus of the new design with the movable arm in the retracted position;

FIG. 3 is a front view of the portable medical diagnostic apparatus of the new design with the movable arm in the retracted position;

FIG. 4 is a rear view of the portable medical diagnostic apparatus of the new design with the movable arm in the retracted position;

FIG. 5 is a top view of the portable medical diagnostic apparatus of the new design with the movable arm in the retracted position;

FIG. 6 is a bottom view of the portable medical diagnostic apparatus of the new design with the movable arm in the retracted position;

FIG. 7 is the first side view of the portable medical diagnostic apparatus of the new design with the movable arm in a deployed position;

FIG. 8 is the second side view of the portable medical diagnostic apparatus of the new design with the movable arm in the deployed position;

FIG. 9 is the front view of the portable medical diagnostic apparatus of the new design with the movable arm in the deployed position;

FIG. 10 is the rear view of the portable medical diagnostic apparatus of the new design with the movable arm in the deployed position;

FIG. 11 is the top view of the portable medical diagnostic apparatus of the new design with the movable arm in the deployed position; and,

FIG. 12 is the bottom view of the portable medical diagnostic apparatus of the new design with the movable arm in the deployed position.
